UNITED STATES PATENT OFFICE.

JOHN F. STEWARD, HERMAN N. KENNEDY, AND BURR A. KENNEDY, OF CHICAGO, ILLINOIS.

GRAIN-HARVESTER.

SPECIFICATION forming part of Letters Patent No. 372,340, dated November 1, 1887.

Application filed August 3, 1886. Serial No. 209,919. (No model.)

To all whom it may concern:

Be it known that we, JOHN F. STEWARD, HERMAN N. KENNEDY, and BURR A. KENNEDY, citizens of the United States, residing 5 at Chicago, in the county of Cook and State of Illinois, have invented certain new and useful Improvements in Grain-Harvesters, which are fully set forth in the following specification, reference being had to the accompanying drawings, forming a part thereof.

This invention consists of improvements on the frame work of the grain-harvester for which there is now pending in the Patent Office our joint application, filed October 19, 15 1885, Serial No. 180,261.

In the drawings, Figure 1 is a front elevation of portions of the harvester and binder frames, parts not needed to illustrate the improvements being omitted or broken away.

20 Fig. 2 is a perspective view from the rear outer quarter of portions of the frame containing our improvements. Fig. 3 is a detail perspective of one of the corners of the frame, showing the mode of securing the uprights.

25 Fig. 4 is a perspective view from the front, looking grainward, of the divider-truss and its connection with the finger-bar. Fig. 5 is a stubble-side elevation of the divider-truss. Fig. 6 is a perspective of the post which forms 30 the strut of the divider-truss, the same being shown in connection with a portion of the finger-bar to which it is secured. Fig. 7 is a plan of the divider-truss and its several braces.

A, B, and C are respectively the outer, 35 middle, and inner trusses.

A' A² are respectively the front and rear outer posts.

B' is the forward inner post.

C' is the rear inner post.

40 The posts A' A² are secured to the upper bar of the outer truss, A. The post B' is secured to the forward end of the upper bar of the middle truss, B. The post C' is secured to the rear sill, S.

45 D D are the bars on which the elevator canvas belts obtain slide-bearings, hereinafter called the "slide-bearing bars."

F F are the sheet-metal sheath-plates which inclose the elevator-canvases.

50 P is the seat-plank.

The posts A', A², B', and C' are bent at the upper part to form the horizontal portions A¹⁰, A²⁰, B¹⁰, and C¹⁰. To the horizontal portions A¹⁰ A²⁰ the slide-bearing bars D D are bolted. Said slide-bearing bars are further 55 bolted to the upright portion of the post C' and to the horizontal portion B¹⁰ of the post C'. The sheath-plates F F are secured by being bound between the slide-bearing bars and said posts.

The horizontal parts B¹⁰ C¹⁰ of the posts B' and C' are substantially at the same level and extend grainward beyond the elevator, and have bolted upon them the seat-plank P. Substantially this structure is claimed in the 65 pending application filed October 19, 1885, Serial No. 180,261, and therefore is not claimed herein.

The mode of securing the posts to the truss-bars is shown in Fig. 3, the upper truss-bars, 7c a' b' c', being of angle-iron. The posts are lapped and bolted onto the vertical flanges a¹⁰ b¹⁰ c¹⁰ of said angle-irons, respectively.

H' is an arm or bar of the binder-frame, which is furnished with bearings on the main frame, in which it may slide when the binder is adjusted back and forward. One of said bearings is the bracket J, which is secured to the top cross-bar, I, which is bolted to the posts A' A² near their bend. The other bearing of 80 the bar H' is formed at J¹⁰ in the bracket J', which is rigidly secured (as by the bolt j¹⁰) to the post A² at its bend. At the inner end of the horizontal part A²⁰ there is secured the bracket J², which comprises the notched sector 85 J²⁰ and the bearing J²¹. In the latter is journaled the rock-shaft K, which has another bearing at J¹¹ in the bracket J', and outside the latter is bent to form the crank-arm K', to which is connected the link L, which is connected also to the binder-frame at l. At the inner end the rock-shaft K has the lever-arm K², vibrating past the notched segment J²⁰, and provided with suitable means for locking it thereto. Said lever-arm K² and the rock-shaft 90 K and its connections thus serve the purpose of adjusting the binder back and forward on the harvester.

Upon the horizontal part B¹⁰ of the post B' are secured the small brackets M M, in which 95 100

is journaled the rock-shaft M' , which has at one end the crank-arm M^{10} and at the other end the lever arm or handle M^{11} , the latter extending up past the notched segment N , which is fixed as a bracket upon the forward portion of the seat-plank. From the crank-arm M^{10} the link M' extends to the tongue, to which it is connected at m^2 . The lever-arm M^{11} is therefore that by which the "tilt" or inclination of the platform is adjusted, commonly called the "tilting-lever."

R is the divider-truss—that is to say, the truss which forms the grain end of the platform-frame and carries the divider. It consists of the upper and lower bars, R' and R^2 , both made of angle-iron, connected at the rear by the clip or clasp R^3 , which grasps the tubular rear sill, S , the bracket or post R^4 , and the grain-wheel guide-post R^5 . The upper and lower bars, R' and R^2 , diverge from their connection with the rear sill to their junction with said post, and the latter, having the lugs R^{10} and R^{11} , forming shoulders over and under which the said bars R' and R^2 respectively bear, forms a strut for the truss. From said post the bars R' and R^2 converge forward and are united at the point of the divider. The post R^4 , below the shoulder R^{10} , is expanded to form the foot R^{12} , and to said foot is secured the finger-bar T , which also forms a front sill of the platform. Said finger-bar is formed of Z -iron, the lower horizontal flange of which affords the opportunity of securing it to the foot R^{12} , while, the vertical web of said Z -iron abutting against the forward side of the foot, said foot R^{12} is firmly braced thereby. Above the shoulder R^{10} the post R^4 has the upward extension R^3 , and to the upper oblique head or sole R^{13} of said extension is secured the divider-board R^6 , which, extending obliquely downward and forward and being sharpened toward the forward end, makes a junction with the forward ends of the upper and lower bars, R' and R^2 .

From the point where the truss-bars cross the finger-bar said truss-bars are bent grainward, so that their vertical plane makes an obtuse angle with the vertical plane of the finger-bar and an acute angle with the line of travel, whereby they gather the grain to the sickle.

To the end of finger-bar, which projects slightly beyond the grain edge of the post R^4 , is secured the brace r^1 , and the guard R^7 , which is fastened at the rear end to the sill S and at the forward end makes a junction with the upper and lower frame-bars, is intermediately bowed grainward and held in that position by the brace r^1 , which is bolted to it at the end. The common junction of the forward ends of the bars R' and R^2 , the board R^6 , and the brace R^7 is covered by the prow r .

The grain-wheel post R^5 is located considerably rearward of the post R^4 and provided with the lugs R^{10} , two projecting above the lower bar, R^2 , and two projecting below the upper bar, R' , of the truss, and thereby said

post R^5 is made to serve as an additional strut for the truss. The same bolt which secures the upper bar, R' , to the post R^4 also takes through the brace R^8 , which is rigidly secured both to the post and to the bar. The bolt which secures the lower bar, R^2 , to the grain-wheel post R^5 at the lower forward lug, R^{10} , also takes through said brace at its rear end, and thereby secures it rigidly both to the lower bar and to the grain-wheel post.

Considering now the portion R^{10} of the bar R^2 from the post R^5 forward to the prow and that portion R^{10} of the bar R' from the post R^4 forward to the prow and the brace R^8 , it will be seen that they constitute a truss independently of the remaining portions of the bars R' and R^2 , and that of said truss the post R^4 forms a strut.

Considering the portion R^{11} of the bar R' from the junction with the post R^4 rearward to the rear sill and the portion R^{12} of the bar R^2 from the junction with the post R^4 rearward to the rear sill and the brace R^8 , it will be apparent that said parts form a truss of which the post R^5 is a strut.

The bolt which secures the upper bar, R' , to the grain-wheel post R^5 at the lug R^{10} also takes through the brace R^8 , which is thus rigidly secured both to the post and to the bar, and extends thence to the extreme grain end of the finger-bar T , to which it is secured a few inches grainward from the intersection of the vertical plane of the truss to the finger-bar.

For the purpose of analyzing the structure to understand how it is braced, the junction of the finger-bar to the post may be treated as coincident with that of the post to the finger-bar. A line in the vertical plane of the truss from such coincident junctions to the lug R^{10} forms the longer leg of a right-angled triangle, of which the shorter leg is a distance grainward on the finger-bar from its junction with the truss to the fastening-brace R^8 , and the said brace forms the hypotenuse of such triangle, and tends, therefore, to prevent the truss and grain-wheel from being laterally distorted.

Considering the portion of the upper bar, R' , from the post R^5 rearward, the portion R^{11} of the lower bar, R^2 , and the brace R^8 treated as if connected at its forward end to the bar R^2 , as it is substantially, by means of the extension T' of the finger-bar and the foot R^{12} of the post R^4 , it will be apparent that said parts constitute a truss, of which the post R^5 is a strut.

By these several braces making the divider frame-work consist of interlaced trusses, the divider is made very stiff and the platform-frame and the grain-wheel are kept very firmly in proper relation.

We claim—

1. In combination with the post Λ^2 and the brackets J^2 and J' , rigidly secured thereto, the latter having the slide-bearing J^{10} for the binder-frame, the rock-shaft K , journaled in

said brackets J' and J^2 , and having the crank-arm to actuate the binder, substantially as set forth.

2. In combination with the trusses having 5 their upper bars formed of angle-iron, the posts bolted to the vertical flange of such angle-iron truss-bars, substantially as set forth.

3. In combination with the finger-bar and the upper and lower bars of the divider-truss, 10 a post, as R^4 , footed on the finger-bar, and having lugs forming shoulders to spread the truss-bars and adapt the post to form the strut of the truss.

4. In combination with the lower bar, R^2 , the 15 portion R^{10} of the upper bar, and the brace R^8 , the post R^4 , constituting a strut for a truss formed by the other parts named, substantially as set forth.

5. In combination with the portion R^{11} of 20 the upper bar, the portion R^{12} of the lower bar, and the brace R^8 , the post R^5 , constituting a strut for the truss formed by the other parts named, substantially as set forth.

6. In combination with the divider-truss, 25 the finger-bar, rigid with the lower bar and extending grainward beyond it, and the brace R^9 , secured to the upper bar and to the grainward extension of the finger-bar, substantially as set forth.

7. In a harvesting-machine, a trussed frame 30 which, as a unitary structure, constitutes both the grain end of the platform and the divider, and having metal upper and lower bars, that portion of said frame which extends between the two sills being parallel with the line of 35 travel, and its said bars being deflected grainward forward of the front sill to cause the divider portion to operate as a gatherer, in combination with a bar, as R^7 , connected to the lower bar of said trussed frame forward 40 of and rearward of the front sill, and a brace extending from the sill grainward to such bar, whereby the said bar and the lower bar of such trussed frame, with the brace, constitute a horizontal truss to stiffen said frame laterally, substantially as set forth. 45

In testimony whereof we have set our hands this 27th day of July, 1886, in the presence of two witnesses, at Chicago, Illinois.
